UNITED STATES PATENT OFFICE.

HENRY A. WISE WOOD, OF NEW YORK, N. Y., ASSIGNOR, BY MESNE ASSIGNMENTS, TO
WOOD NEWSPAPER MACHINERY CORPORATION, OF NEW YORK, N. Y., A CORPORA-
TION OF VIRGINIA.

MATRIX-ROASTER.

1,162,672.

Specification of Letters Patent. Patented Nov. 30, 1915.

Application filed February 10, 1908. Serial No. 415,264.

To all whom it may concern:

Be it known that I, HENRY A. WISE Wood, a citizen of the United States, residing at New York, in the county of New York and 5 State of New York, have invented a new and useful Matrix-Roaster, of which the following is a specification.

This invention relates to an apparatus for, and method of, roasting stereotypers' papier 10 maché matrices.

At the present time matrices, after they have been baked preliminarily in contact with the form, are removed and put into a roaster, for the purpose of completing the 15 roasting. These, and all other methods of drying or roasting now in use require separate pieces of apparatus, such as a rotary gas heated roaster, heated table, or the like and these take up space and consume fuel, 20 and in fact some of them require power. Moreover, no such devices can bring the temperature of the matrix to that of the molten metal which is to be cast against the matrix so that when the matrix afterward 25 is used, steam will not be generated.

The principal object of the present invention is to provide for bringing the matrix up precisely to the temperature of the metal which is going to be used in casting from it, without employing any additional apparatus which takes up floor space, extra fuel or power; also to provide a convenient arrangement by which the matrix is brought into a position near the casting apparatus in which it is near the place where it is to be used; and to provide means whereby the matrix can be dropped in and quickly removed without any special guides or apparatus for bringing it into proper position. In this way it will be seen that the disadvantages of the old system are avoided, and that as the matrix is brought up to the temperature of the metal which is to be cast against it, no steam will be generated when the cast is made.

Reference is to be had to the accompanying drawings which show one way in which these objects may be obtained, and in which—

Figure 1 is a sectional view of a melting pot showing the roaster applied thereto. Fig. 2 is a plan of a portion of the same, Fig. 3 is an elevation of a hook employed

for transferring and removing the matrices, and Fig. 4 is a sectional view showing a 55 modification.

In order to accomplish the above mentioned results according to this invention, the matrices are removed from the form and then subjected to the temperature of the 60 molten metal from which the stereotype plates are to be cast by introducing them into the body thereof, but out of direct contact therewith. In this way they are heated by heat from the body of molten metal and 65 thus are brought exactly to the proper temperature.

Referring now to the drawings, it will be seen that the invention is shown as applied to an ordinary form of melting pot 10 in 70 which is located a receptacle 11 for receiving the matrices. This receptacle may be located at the side of the receptacle, and form one side of it, as shown in Fig. 4, or may be located entirely within the body of 75 the metal as shown in the other figures, projecting from one side of the receptacle so that the molten metal may come into contact with all sides of the receptacle. It is preferably placed in inclined position so 80 that the matrices may be introduced into it easily and so that the steam and gases arising from the matrix as it dries may find a ready escape into the outer air above the metal in the melting pot. 85

In order to fasten the receptacle to the side of the melting pot, the former is provided with an angular lip 12 which can be bolted to the flange on the melting pot as indicated. It is also shown as provided 90 with ribs 13 on both sides, these ribs preferably intersecting each other, so that the receptacle may be made of comparatively light material and preserve its strength, and may receive the heat readily from the molten 95 metal. It is shown at its edges as shaped to correspond to the shape of the melting pot, the lip 12 being preferably of segmental form in case it is applied to a round pot. By inclining the receptacle in this way, the 100 bottom of it is located comparatively near the flame or other source of heat by which the metal is heated.

In order to manipulate the matrix in a convenient and simple manner, a hook is 105 preferably used comprising a body-portion

or bar 15 having an angular projection 16 at the top and on one side to which the handle 17 is connected, and provided with a pair of diverging legs 18, at the bottom, on the 5 side of which, opposite to that on which the handle is located, are hook-shaped supports 19 on which the bottom of the matrix is adapted to rest. It will be noted that the matrix rests against the flat surface of the 10 bar 15 when supported by the supports 19. In this way the matrix may be handled with one hand in a very simple manner, and introduced into and drawn from the receptacle without any special care or any 15 guiding arrangement.

The way in which the apparatus is used will be obvious. As it is desirable that the matrix be dried in part in contact with the type and the drying completed after it is 20 taken from it, it is left in contact with the form for a short time only, and is then applied to the hook and transferred to the receptacle 11, where it speedily reaches the 25 temperature of the molten metal, and is thoroughly dried. When the matrix is removed it is obvious that it is in such condition that when placed in the mold and the molten metal is brought against it, it will not be raised to any higher temperature than 30 it has already reached. Consequently steam, which is injurious to the casting, will not be generated.

While I have illustrated and described a preferred embodiment of the invention, I am 35 aware that many modifications may be made therein by any person skilled in the art without departing from the scope of the invention as expressed in the claims. I do not wish therefore to be limited to the details 40 of construction shown and described, but

What I do claim is:—

1. An apparatus for roasting stereotype matrices comprising a melting pot for the stereotype metal to be cast against the matrices having a permanent fixed receptacle 45 therein for receiving matrices.
2. The combination with a melting pot, of a receptacle for matrices located therein, in inclined position and secured to the edge 50 of the pot.
3. The method of roasting a stereotype matrix suitable for making a cast from a metal which consists in introducing it edge foremost below the surface of a body of that metal in a molten condition and leaving it 55 there until dried.
4. The method of roasting a stereotype matrix which consists in introducing it into a body of molten stereotype metal but out of direct contact therewith.
5. The method of roasting stereotype matrices which consists in preliminarily 60 drying them on the form and thereafter substantially surrounding them by a body of molten metal of the kind which is to be cast 65 on the matrix.
6. The method of roasting stereotype matrices which consists in removing them from the form and subjecting them to the temperature of casting, by introducing them 70 from above under the surface of a body of molten metal from which the cast is to be made.

In testimony whereof I have hereunto set my hand, in the presence of two subscribing 75 witnesses.

H. A. WISE WOOD.
